UNITED STATES PATENT OFFICE.

AUGUST F. HABENICHT, OF TINLEY PARK, ILLINOIS.

ACETYLENE-GAS AND PRESSURE GENERATOR.

1,383,464.

Specification of Letters Patent.

Patented July 5, 1921.

Application filed March 18, 1920. Serial No. 366,755.

To all whom it may concern:

Be it known that I, AUGUST F. HABENICHT, a citizen of the United States, residing at Tinley Park, in the county of Cook 5 and State of Illinois, have invented certain new and useful Improvements in Acetylene-Gas and Pressure Generators, of which the following is a specification.

This invention relates to gas generators 10 of that class employed in the generation of acetylene from calcium carbid, and has particular relation to that kind of such generators in which the carbid is supplied to or fed into water or decomposing liquid there- 15 for instead of the water being supplied to the carbid, and it consists in certain peculiarities of the construction, novel arrangement, combination and operation of the various parts thereof as will be herein- 20 after more fully set forth and specifically claimed.

The principal object of the invention is to furnish a gas generator of the above mentioned general character, which shall be simple and inexpensive in construction, strong, durable, safe and efficient in operation, and which is more particularly intended for use in shop work for welding purposes, yet may be used for the generation and supply of 30 gas for illuminating or heating purposes.

Another object is to provide a gas generator which shall be automatic in its operation, after being charged or loaded with suitable supplies of water and carbid.

Various other objects and advantages of the invention will be disclosed in the following description and explanation.

In the accompanying drawings, which serve to illustrate an embodiment of the invention—

Figure 1 is a general view mainly in elevation and partly in section of a gas generator embodying my invention.

Fig. 2 is a top plan view of the combined 45 generator tank and gasometer.

Fig. 3 is a central vertical sectional view taken on line 3—3 of Fig. 1, looking in the direction indicated by the arrows.

Fig. 4 is a similar view of like parts taken 50 on a line at right angles to that on which Fig. 3 is taken, and

Fig. 5 is a plan sectional view taken on line 5—5 of Fig. 3 but showing the carbid receptacle removed.

55 Like numerals of reference refer to corre-

sponding parts throughout the different views of the drawings.

The reference numeral 7 designates the combined generator tank and gasometer, which may be made of any suitable size, 60 form and material, but by preference cylindrical in shape as shown. This tank is mounted on a suitable support 8 and has in its lower end a depending outlet tube or member 9 for the discharge of the contents 65 of the tank 7 when it is desired to clean the same.

The tube or member 9 has on opposite sides thereof spaced apart lugs 10 between each pair of which is pivotally mounted a 70 screw-threaded bolt 11 which bolts are adapted to enter diametrically opposed slots 12 in a head or cap 13 used for closing the outlet 9 or said tube.

The head or cap 10 is held in place by 75 means of wing nuts 14 engaging the screw bolts 11, and it is obvious that the cap may be removed from the outlet 9 by disengaging said nuts from the bolts on which they are mounted.

The upper end of the tank 7 is provided with an inlet 15 which is equipped with a closure of similar construction and arrangement to that just above described in connection with the outlet 9 or discharging 85 tube.

The tank 7 is mounted on the support 8 so that its outlet 9 will extend downwardly through an opening therein, and by reference to Figs. 1, 3 and 4 of the drawings, it 90 will be seen that the top of said tank is provided with a pressure indicator 16 of the ordinary or any well known construction used for the purpose of indicating the pressure contained in the tank. Closely secured to the lower surface of the top of the tank 7 by means of screw bolts 17 or otherwise is an annular flange 18 on the upper end of the carbid receptacle 19 which may be made of any suitable size, form and material. The flange 18 of this receptacle surrounds the inlet 15 so that the carbid can be readily placed in its container. Located horizontally and a slight distance below the container 19 is a shelf or platform 20 which 100 is supported by means of brackets 21 secured to the edges thereof and to the sides of the carbid container as will be readily understood by reference to Figs. 3 and 5 of the drawings.

As shown in Fig. 3 the shelf or platform 20 has at one of its ends an angular extension 22 the vertical wall 23 of which is located inwardly from the front wall of the 5 container 19, while its floor 24 extends horizontally and forwardly of said wall. The front wall of the container 19 is provided with a doorway 25 in its lower portion which is closed by a door 26 secured by 10 means of hinges 27 at its upper end to the carbide container. This door is normally held closed by means of a spring 28 which is secured at one of its ends to the inner surface of the door and at its other end to 15 the rear wall of the container 19. Slidably located on the upper surface of the platform 20 is a carbide feeding member which consists of a flat plate 29 having at its front end a downwardly extended flange 30 which 20 coincides with the vertical portion 23 of the extension 22 of the shelf or platform 20.

Transversely journaled in suitable hangars 31 on the lower surface of the platform 20 is a horizontally disposed shaft 32, which 25 as shown in Figs. 1 and 3, extends through the wall of the tank 7. This shaft is provided at a point about the middle of the platform 20 with an upwardly extended crank arm 33 which projects through a slot 34 in 30 the platform and engages an opening 35 in the feeding slide 29 so that when the shaft 32 is rocked, said slide will be moved back and forth to the end that, the flange 30 on the slide will force off the quantity of carbide 35 held on the floor 24 of the extension 22 of the platform 20 and allow it to drop into the water 36 contained in the lower portion of the generating tank as will be readily understood by reference to dotted lines in Fig. 3 40 of the drawings.

In the above stated operation, it will be understood that the door 26 will be moved forwardly to about the position shown by dotted lines in Fig. 3, in the forward movement of the feeding slide 29 and its flange 30 by reason of the carbide interposed between the door and said flange. In the return movement of the slide 29 the spring 28 will retract or close the door 26 as is obvious.

The bearing in the wall of the tank 7 for the shaft 32 is provided with a suitable packing 37 and a gland 38 to hold said packing in place so as to prevent the escape 55 of gas. Rigidly secured to the outer portion of the shaft 32 is a crank arm 39 which is pivotally connected at its other end to a rod or bar 40 which extends laterally from the tank and is loosely connected by means of a link 41 to the piston rod 42 of a plunger 43 located in a cylinder 44 which is centrally supported in a receptacle 45 containing glycerin or a similar substance. The receptacle 45 is supported by means of brackets 65 46 on and below the support or table 8 di-

rectly under a drum 47 which is transversely journaled on and above the table or support 8 or rather on brackets 48 extended upwardly from said table. That end of the rod or bar 40 to which the link 41 is secured is 70 also pivotally secured to a wrist pin 49 eccentrically located on one end of the drum 47.

The cylinder 44 within the liquid container 45 is provided in its lower end with a port 50 which port has in its lower portion a valve seat 51 for a needle valve 52 adjustably mounted in the lower end of the cylinder 44 and container 45 which valve is employed to regulate the quantity of glycerin or other suitable liquid passing to and from 80 the container 45 and the cylinder 44 through the port 50 in said cylinder.

The drum 47 carries a ratchet wheel 54 which rotates therewith. Mounted on the table or support 8 near the drum and preferably crosswise thereof is a bracket 55 to one of the uprights of which bracket is pivotally secured a pawl 56 which is adapted to engage with its free end the teeth of the ratchet wheel 54. This pawl is normally held out of engagement with the ratchet wheel by means of a spring 57 one end of which is secured to the pawl and the other end to a screw bolt 58 located in a suitable opening in the bracket 55. The tension of 95 the spring 57 can be regulated by means of a wing nut 59 engaging the upper portion of said bolt.

Supported on the bracket 55 is a cylinder 60 in which is located a plunger 61 which 100 has its piston rod 62 extended through the lower end of said cylinder and pivotally connected to the pawl 56 between its pivot and the spring 57. Connecting the upper portion of the cylinder 60 to the gasometer or tank 7 is a pipe 63 which it will be observed is located in the upper portion of said tank.

Secured at one of its ends to the drum 47 and wound thereon is a cable 64 which passes over blocks 65 suitably supported overhead 110 and carries at its other end a weight 66 which is also connected to the cable by means of a block 67 around which as well as one of the blocks 65 the cable can be 115 driven as many times as desired.

Located at any suitable distance from the tank 7 is an extension tank 68 which has communication through a pipe 69 with the upper portion of the gasometer or generating tank as is clearly shown in Figs. 1 and 120 3 of the drawings. The pipe 69 is provided with a valve 70 to control or shut off the flow of gas from the generating tank to the extension tank. The latter tank has communicating therewith one end of a service 125 pipe 71 which may lead to any desired point and to which a welding tool may be connected in the well known way, or if desired, said service pipe can be suitably connected to light fixtures.

From the foregoing and by reference to the drawings it will be readily understood and clearly seen that, assuming that the carbid receptacle is filled or supplied with carbid and that the closures 13 as well as the valve 70 are closed, and it is desired to start the operation of the apparatus, it is only necessary to cause enough carbid to be discharged from the receptacle 19 into the water 36 contained in the tank 7 to generate a sufficient amount of gas to fill the gasometer or tank 7 from which it can be transferred through the pipe 69 to the extension tank 7 by opening the valve 70 in the last named pipe. As the drum 47 is rotated by means of the weight 66 and cable 64 it is apparent that the rod or bar 40 will be reciprocated and through its connections with the feeding slide 29, the latter will be moved back and forth in which operation lumps 72 of carbon will be forced off the floor 24 of the extension 22 into the water. This operation will continue until the pressure within the tank 7 rises to such an extent as to cause the plunger 61 in the cylinder 60 to be depressed, which operation will cause the pawl 56 to engage the ratchet wheel 54 on the drum and to stop its movement until the pressure within the tank 7 has been diminished by usage to such an extent as to permit the pawl 56 to be disengaged from the ratchet wheel 54, when it is obvious that the weighted cable will again set the drum in motion.

In order to regulate the movement of the drum, the plunger 43 in the cylinder 44 with its connections with the drum is employed, for it will be observed that the movement of the plunger 43 can be regulated by adjusting the valve 52 so as to increase or diminish the size of the port 53 in the cylinder 44 so as to permit the glycerin to pass to and from the cylinder 44 freely or very slowly.

Having thus fully described my invention, what I claim as new and desire to secure by Letters Patent is—

1. In an apparatus of the class described, the combination with a generating tank adapted to hold water in its lower portion and having an inlet and an outlet therefor, of a carbid receptacle mounted within the upper portion of said tank and having an outlet in its lower portion, a feeding slide mounted below said outlet, a rotary drum located near said tank, connections uniting the feeding slide and drum and eccentrically connected to the latter, means to rotate the drum, and means eccentrically connected to the drum to regulate the speed of the movement thereof, said last named means including a valved cylinder and a plunger therein operable by said drum.
2. In an apparatus of the class described, the combination with a generating tank adapted to hold water in its lower portion and having an inlet and an outlet therefor, of a carbid receptacle mounted within the upper portion of said tank and having an outlet in its lower portion, a feeding slide mounted below said outlet, a rotary drum located near said tank, connections uniting the feeding slide and drum and eccentrically connected to the latter, means to rotate the drum, means eccentrically connected to the drum to regulate the speed thereof, said last named means including a valved cylinder and a plunger therein operable by said drum, and means operable by the pressure within the tank to stop the movement of the drum.

AUGUST F. HABENICHT.
